Primary Examiner — Deanna L Pratt*Assistant Examiner* — Ieisha Price(74) *Attorney, Agent, or Firm* — Dorsey & Whitney LLP(57) **CLAIM**

I claim the ornamental design for a bag port, substantially as shown and described.

DESCRIPTION

FIG. 1 is a bottom, right, rear perspective view of a bag port. FIG. 2 is a top, right, front perspective view of the bag port of FIG. 1.

FIG. 3 is a top, right, rear perspective view of the bag port of FIG. 1.

FIG. 4 is a rear plan view of the bag port of FIG. 1.

FIG. 5 is a left side elevation view of the bag port of FIG. 1.

FIG. 6 is a right side elevation view of the bag port of FIG. 1.

FIG. 7 is a top elevation view of the bag port of FIG. 1.

FIG. 8 is a bottom elevation view of the bag port of FIG. 1; and,

FIG. 9 is a right rear perspective view in cross section as indicated in FIG. 4 of the bag port of FIG. 1.

The broken lines in the drawings illustrate portions of the bag port which form no part of the claimed design.
